ADJUSTABLE WOOD PLUG CUTTER

Murray E. Myers, Lindenhurst, N. Y.

Application November 26, 1947, Serial No. 788,305

7 Claims. (Cl. 145—120)

(Granted under the act of March 3, 1883, as
amended April 30, 1928; 370 O. G. 757)

1

This invention relates to improvements in cutters, and more particularly pertains to improvements in plug cutters whereby a range of diameters of plugs can be machined quickly and facilely.

Conventional methods of cutting wood plugs have included the use of a solid head wherein a bit is inserted, and the use of a sleeve saw. However, such devices are of limited application and efficiency: Adjustment within a range of sizes of plugs cannot be obtained readily, it being necessary to employ a different cutting tool for each size of plug to be cut. Cutting blades of such devices tend to wear rapidly and to break frequently in use. In addition, plugs cut by such means are inferior, being usually oval rather than true-round in shape.

The primary object of the invention is to provide a plug cutter of simple and durable construction adapted to cut a range of sizes of true-round plugs.

Another object is to provide a plug cutter that can be pre-set accurately and facilely to cut a predetermined size plug.

Still another object is to provide a plug cutter having eccentric elements and Stellite cutting edges whereby a range of sizes of plugs can be cut on drill press, lathe, plug manufacturing, and similar machines.

Further objects and advantages of this invention, as well as its construction, arrangement and operation, will be apparent from the following description and claims in connection with the accompanying drawing, in which

Fig. 1 is a plan view of a plug cutter, showing a preferred embodiment of the invention;

Fig. 2 is an elevation thereof; and

Fig. 3 is a section thereof taken on the line 3—3 of Fig. 2.

Similar numerals refer to similar parts throughout the several views.

Spindle 11 is provided with a threaded bore 13 extending into one end thereof, whereby said spindle is secured on the rotatable shaft of a machine (not shown), and a bore 15 eccentric to the common longitudinal axis of said spindle and said threaded bore extending into the opposite end thereof and communicating with said threaded bore. A plurality of setscrews 17 are threaded in spaced relation into said spindle, said setscrews being adapted to secure a bushing, hereinafter described, seated in said eccentric bore.

Bushing 19 is a split ring adapted to be carried snugly in said eccentric bore, said bushing being

2

provided with a flanged end 21 adapted to abut a face of said spindle, and with an eccentric bore 23 cut therethrough. Preferably, said bore 23 is of such eccentricity that rotation of said bushing 5 180° from the position shown in Figs. 1 and 3 makes the longitudinal axis of said bore 23 coincident with the longitudinal axis of threaded bore 13.

Cutter head 25 comprises a shank 27 adapted 10 to be carried in bore 23 of bushing 19 and an integral blade portion, hereinafter described. Said shank includes an axial bore 29 to facilitate centering and alignment of the tool, a flange portion 31 adapted to abut bushing 19, and a plurality of longitudinal slots 33 aligned with the cutting blades hereinafter described and adapted 15 to carry the auxiliary cutter hereinafter described. The integral blade portion comprises a cylindrical sleeve 35 carrying diametrically opposed blades 37 and 39, which are oppositely disposed, as shown. Each of said blades is saw-tooth shaped, and is provided with a Stellite welded and ground cutting edge. Said blades are designed with suitable cutting-edge angle, relief, back rake and side rake, for the uses intended. 20 Chip ports 41 are provided in the wall of the cutter head to facilitate plug removal and to prevent binding the cutter.

Auxiliary cutter 43 is carried in slot 33 of cutter head 25, and is provided with a Stellite welded and ground cutting edge 45. Said cutting edge 45 is designed with a suitable cutting-edge angle, relief, back rake and side rake so as to be adapted 25 for use in chamfering and tapering the plug being cut. Bolt 41, carried slidably in slot 49 of cutter 43, is threaded into shank 27 to secure said auxiliary cutter in selected position.

In operation, when it is desired to cut a plug of minimum diameter, the component elements 30 are assembled in the manner shown and mounted on a suitable machine. By reason of the eccentricity of the cutters, cutter 39 is effective to cut clearance, while cutter 37 finishes and auxiliary cutter 43 chamfers and tapers the 35 plug. To cut a plug of maximum diameter, the bushing 19 is rotated 180° from the position illustrated until the axes of cutters 37 and 39 and of spindle 11 are coincident, and secured in that 40 position by means of setscrews 17. Intermediate sizes can be cut by securing said bushing 45 in an intermediate position.

Various modifications and changes can be 50 made in the subject device without departing from the scope of the invention.

The invention described herein may be manu-

factured and used by or for the Government of the United States of America for governmental purposes without the payment of any royalties thereon or therefor.

I claim:

1. A plug cutter comprising a spindle adapted to be secured on a rotatable shaft, a first eccentric bore in said spindle, a bushing mounted rotatably in said first bore, said bushing having a second eccentric bore, means to retain said bushing against rotation, and a cylindrical sleeve cutter secured in said second bore, the axis of said cutter having a maximum displacement from the axis of said spindle that is less than the radius of said cutter.

2. A plug cutter comprising a spindle adapted to be secured on a rotatable shaft, a first eccentric bore in said spindle, a bushing mounted rotatably in said first bore, means to secure said bushing against such rotation, a second eccentric bore in said bushing, and a cylindrical sleeve cutter secured in said second bore, the axis of said cutter having a maximum displacement from the axis of said spindle that is less than the radius of said cutter.

3. A plug cutter comprising a spindle adapted to be secured on a rotatable shaft, a first eccentric bore in said spindle, a bushing mounted rotatably in said first bore, means to secure said bushing against such rotation, a second eccentric bore in said bushing, and a cylindrical sleeve cutter having a plurality of cutting blades secured in said second bore, the axis of said cutter having a maximum displacement from the axis of said spindle that is less than the radius of said cutter.

4. A plug cutter comprising a spindle adapted to be secured on a rotatable shaft, a first bore in said spindle eccentric the axis of rotation thereof, a split-ring bushing mounted rotatably in said first bore, means to secure said bushing against such rotation, a second bore in said bushing disposed eccentric to the longitudinal axis of said bushing, and a cylindrical sleeve cutter having a plurality of cutting blades secured in and extending beyond said second bore, the axis of said cutter having a maximum displacement from the axis of said spindle that is less than the radius of said cutter.

5. A plug cutter comprising a spindle adapted to be secured on a rotatable shaft, a first bore in said spindle eccentric the longitudinal axis thereof, a split-ring bushing mounted rotatably in said first bore, means to secure said bushing against such rotation, a second bore in said bushing disposed eccentric to the longitudinal axis of said bushing, the eccentricity of said first and second bores being substantially equal, and

a cylindrical sleeve cutter having a plurality of cutting blades secured in and extending beyond said second bore, the axis of said cutter having a maximum displacement from the axis of said spindle that is less than the radius of said cutter.

6. A plug cutter comprising a spindle adapted to be secured on a rotatable shaft, a first bore in said spindle eccentric the longitudinal axis thereof, a split-ring bushing mounted rotatably in said first bore, means to secure said bushing against such rotation, a second bore in said bushing disposed eccentric to the longitudinal axis of said bushing, the eccentricity of said first and second bores being substantially equal, a cylindrical sleeve cutter having a pair of opposed cutting blades secured in and extending beyond said second bore, the axis of said cutter having a maximum displacement from the axis of said spindle that is less than the radius of said cutter, and a chamfering cutter secured to said cutter in axial alignment with one of said blades.

7. A plug cutter comprising a spindle adapted to be secured on a rotatable shaft, a first bore in said spindle eccentric the longitudinal axis thereof, a split-ring bushing mounted rotatably in said first bore, means to secure said bushing against such rotation, a second bore in said bushing disposed eccentric the longitudinal axis of said bushing, the eccentricity of said first and second bores being substantially equal, a first cutter comprising a sleeve carried on an integral shank, said shank having an axial bore and being secured in said second bore, said sleeve carrying a plurality of Stellite cutting edges on the rim thereof distal said shank, the axis of said rim having a maximum displacement from the axis of said spindle that is less than the radius of said rim, and a second cutter carried in a slot in said shank in axial alignment with one of said cutting edges.
